(57) **CLAIM**

The ornamental design for a jacket, as shown and described.

DESCRIPTION

FIG. 1 is a rear perspective view of a jacket showing our new design in an in-use configuration;

FIG. 2 is a front view thereof;

FIG. 3 is a rear view thereof;

FIG. 4 is a right side view thereof;

FIG. 5 is a left side view thereof; and,

FIG. 6 is a top view thereof.

The darker areas of stippled shading shown in FIGS. 1, 4 and 5 represent a contrast in appearance only. The broken lines immediately adjacent to the shaded area represent unclaimed boundaries of the design. The broken lines showing the remainder of the jacket are for environmental purposes only and form no part of the claimed design.
